(57) **CLAIM**

The ornamental design for a carrier with lid, as shown and described.

DESCRIPTION

FIG. 1 is a front perspective view of a carrier showing my new design.

FIG. 2 is a rear perspective view of the carrier of FIG. 1.

FIG. 3 is a front elevation view of the carrier of FIG. 1.

FIG. 4 is a right elevation view of the carrier of FIG. 1.

FIG. 5 is a rear elevation view of the carrier of FIG. 1.

FIG. 6 is a left elevation view of the carrier of FIG. 1.

FIG. 7 is a top plan view of the carrier of FIG. 1.

FIG. 8 is a bottom plan view of the carrier of FIG. 1; and,

FIG. 9 is a plan view of the carrier of FIG. 1 shown in an

unfolded configuration.

The broken lines depict environmental subject matter. The broken lines shown adjacent to shaded regions represent the bounds of the claim. The broken lines form no part of the claimed design.
